UNITED STATES PATENT OFFICE

169,074

VEHICLE SEAT

John H. Lang, Detroit, Mich.

Application June 17, 1952, Serial No. 20,225

Term of patent 3½ years

(Cl. D14—6)

To all whom it may concern:

Be it known that I, John H. Lang, a citizen of the United States of America, residing in Detroit, county of Wayne, State of Michigan, have invented a new, original, and ornamental Design for a Vehicle Seat, of which the following is a specification, reference being had to the accompanying drawings, forming a part thereof in which:

Fig. 1 is a perspective view of a vehicle seat, embodying my new design.

Fig. 2 is a top plan view.

The characteristic features of my design reside in the portions shown by means of full lines in the drawings.

I claim:

The ornamental design for a vehicle seat, substantially as shown and described.

JOHN H. LANG.
